UNITED STATES PATENT OFFICE.

CURTIS H. WALKER, OF CHICAGO, ILLINOIS.

ADJUSTABLE MAP-RACK.

1,251,145.

Specification of Letters Patent. Patented Dec. 25, 1917.

Application filed February 26, 1917. Serial No. 150,952.

To all whom it may concern:

Be it known that I, CURTIS H. WALKER, a citizen of the United States, residing at Chicago, in the county of Cook and State of Illinois, have invented a new and useful Improvement in Adjustable Map-Racks; and I do hereby declare the following, when taken in connection with the accompanying drawings and the characters of reference 5 marked thereon, to be a full, clear, and exact description of the same, and which said drawings constitute part of this application, and represent, in—

Figure 1 a view in front elevation of 15 one form which a map-rack constructed in accordance with my invention may assume, showing the application to it of three maps.

Fig. 2 a view in elevation of the rack-frame from which the sliding bracket-blocks have been removed.

Fig. 3 a detail sectional perspective view on the line 3—3 of Fig. 1.

Fig. 4 a view in horizontal section on the line 4—4 of Fig. 1.

Fig. 5 a view in vertical section on the line 5—5 of Fig. 1.

My invention relates to an improvement in map-racks, the object being to provide a simple and convenient map-rack designed 20 and constructed with particular reference to accommodating maps of varying width.

With these ends in view, my invention consists in a map-rack having fixed map-roller brackets applied to its ends, and intermediate adjustable map-roller brackets 25 for coöperation therewith.

My invention further consists in certain details of construction as will be herein-after described and pointed out in the 30 claims.

In carrying out my invention as herein shown, I employ a rectangular rack-frame 6 provided at its respective ends and upon its front face, with vertically arranged 35 cleats 7 to which map-roller brackets 8 are applied in vertical series, these brackets being provided with perforations 9 for the reception of trunnions 10 at the ends of the rollers 11 of the maps 12.

To adapt my improved map-rack to accommodate maps shorter than the full distance between the complementary brackets 40 at the opposite ends of the rack-frame, I provide the frame with sliding bracket-blocks 13 each carrying two map-roller brackets 14, 15, having slots 16 at its re-

spective ends. For mounting the blocks 13 slidably with respect to the frame, the same is formed with a series of horizontal slots 17 located one above the other in line with the complementary pairs of brackets, there being as many bracket-blocks 13 and slots 17 as there are complementary pairs of brackets. The said slots 17 are T-shaped in cross-section for the reception of the 45 heads of the bolts 19 by means of which the blocks 13 are slidably mounted upon the frame 6, the said bolts extending forwardly through the slots 17 and through the blocks 13 and having their projecting ends threaded 50 for the reception of wing-nuts 20 under which are placed washers 21 bearing directly upon the outer faces of the blocks 13. Pins 22 mounted in the respective ends of the blocks 13, enter the slots 17 and prevent the 55 blocks 13 from canting by turning on the bolts 19. By loosening its wing-nut 20 any one of the blocks 13 may be moved to the left or to the right, according as it is desired to position its slotted left hand 60 bracket 14 with respect to the complementary left hand perforated bracket 8 of the complementary pair of brackets between which the block is located, or to the right to position the right hand slotted 65 bracket 15 with respect to the right hand perforated bracket 8 of the same pair. The moving of the bracket-block, as above described, to the right or left is determined by the desired location of the map upon the 70 rack. After the block has been moved into the desired position, its wing-nut is turned home, whereby the block is solidly fastened in place after which the map is applied by the insertion of its trunnions 10 into the 75 perforation and slot of the two brackets thus brought into coöperative relation.

As shown, the perforated brackets have been applied to the cleats 7 and the slotted brackets to the sliding blocks 13, but this 80 arrangement may be reversed, if desired. The capacity of my improved map-rack may be increased or decreased by increasing or decreasing the height and length of the frame 6 and correspondingly increasing 85 or decreasing the number of map-roller brackets.

I claim:—

1. In a map-rack, the combination with the frame thereof, of complementary pairs 90 of map-roller brackets fixed to the ends of the said frame, and adjustable map-roller

brackets located between the brackets of the complementary pairs on the frame.

2. In a map-rack, the combination with the frame thereof, of complementary pairs of map-roller brackets fixed to the ends thereof, longitudinally movable sliding bracket-blocks applied to the frame so as to be adjusted in either direction in line with the complementary pairs of brackets, and a 10 pair of map-roller brackets applied to each of the said blocks.

3. In a map-rack, the combination with a frame formed with longitudinal slots arranged one above the other, of complementary pairs of map-roller brackets applied to the ends of the said frame in line with the 15

said slots, bracket-blocks applied to the said frame over the said slots, means for slidably fastening the blocks to the frame through the said slots, and map-roller brackets carried by the said blocks which are adjusted in either direction for positioning their map-roller brackets with respect to the fixed map-roller brackets upon the frame. 20

In testimony whereof, I have signed this 25 specification in the presence of two subscribing witnesses.

CURTIS H. WALKER.
